FLOW CONTROLLER

Henry U. Garrett and Clifford M. Peters, Longview, Tex., assignors, by direct and mesne assignments, to Garrett Oil Tools, Inc., Houston, Tex., a corporation of Texas

Application August 29, 1947, Serial No. 771,159

7 Claims. (Cl. 137—145)

1

This invention relates to improvements in flow controllers and refers more particularly to flow controllers adaptable to be interposed in a pipe line or other conduit to provide a means for controlling the flow through the conduit in a manner to permit flow through the conduit periodically at predetermined time intervals.

Apparatus in accordance with this invention may be used for example for controlling the flow of gas in gas lift operations in the production of oil from well bores where it is necessary to intermittently introduce a charge of lifting fluid under pressure into a column of liquid. The controllers of this invention have many other uses and this specific use is given by way of illustration and not by way of limitation.

An object of this invention is to provide a simple and economical controller for flow through a conduit.

Another object is to provide a simple and economical controller for flow through a conduit in which the flow takes place during predetermined time intervals.

A further object is to provide a simple economical controller for flow through a conduit wherein flow is provided for during predetermined time intervals in which the conduit will not be open for flow during any of the time intervals in the event the pressure on the downstream side of the controller exceeds a predetermined amount.

Yet another object is to provide a simple economical controller for flow through a conduit wherein flow is provided for during predetermined time intervals, in which the length of the time intervals during which flow occurs may be varied.

Still another object is to provide as a sub-combination for a flow controller a time controlled mechanism in which the length of a predetermined number of time intervals may be readily varied.

Other and further objects of this invention will appear from the following description:

In the accompanying drawings which form a part of the instant specification and are to be read in conjunction therewith, the single figure illustrates schematically in elevation and installation of a flow controller embodying this invention wherein parts are shown in section for added clarity.

Referring to the drawings, the flow controller is illustrated in conjunction with a well head 5 of a producing oil well which is equipped for operation by what is known as the gas lift method. In this particular installation the well head 5 is mounted upon the upper end of an oil string of casing 6. Suspended concentrically within the casing 6 is a string of flow tubing 7. This equipment may be in accordance with con-

2

ventional practices and in the interest of simplicity a more detailed illustration of the well bore equipment is not shown in the drawings. It is to be understood, however, that the string of tubing is equipped with suitable gas lift valves at proper intervals throughout its length and that in operation gas or other lifting fluid is introduced, in this example, into the annulus formed between the casing 6 and the tubing 7. This gas is introduced through conduit 8.

In gas lift operations the gas is introduced into the casing tubing annulus intermittently and the gas lift valves, which are pressure responsive valves, are operated by the pressure variations of the fluid in the annulus. The controller of this invention forms a compact unit that may be readily mounted upon the conduit 8 and governs the flow of fluid through the conduit into the annulus so that lifting fluid under pressure is introduced into the annulus periodically at predetermined time intervals, but the arrangement of the controller is such that the motor valve will not open even during one of the predetermined time intervals if for any reason the pressure within the annulus is greater than a predetermined amount. Obviously such a pressure condition would occur only in the event of unusual circumstances in which case it is desirable that the line 8 be kept in a closed condition.

With regard to the flow controller, which constitutes the invention, it is made up of a motor-valve 9 and a time controller 10. The motor-valve comprises a valve body 11, a valve stem housing 12, head bushing 13 and a two part diaphragm casing 14.

The motor-valve may be interposed in conduit 8 as body 11 has threaded connections at both ends. The body has a partition 15 across the passage therethrough. The partition has an opening with a seat ring 16 threaded therein. A boss 11a, formed on the body, threadedly receives the lower end of valve stem housing 12. The valve stem housing has a central bore with an enlarged portion 12a. Within the bore of the housing is slidably mounted a part 17 of the valve stem. This part has a portion of enlarged diameter which resides within the portion 12a of the housing bore. A seal is provided between the housing and part 17 by O-rings 18 disposed in peripheral grooves in the enlarged diameter portion of part 17 to prevent escape of fluid under pressure. The part 17 may be equipped with other types of packing or sealing material such as for instance chevron packing in lieu of the O-rings but the O-rings have been found to be entirely satisfactory for this purpose and due to the very low friction involved in their use are preferred. Also, a bellows type seal may be employed. The part 17 carries valve member 19 at its lower end. The valve member is in the

form of a hemisphere and is adapted to seat on seat ring 16 to close off the passage through the valve member and control flow through conduit 8.

The bushing 13 has a threaded connection with the upper end of housing 12 and has a central bore axially aligned with the bore of the housing. Another part 20 of the valve stem is slidably inserted within the bore of bushing 13 and extends from the upper end thereof through a bore in the lower part of the diaphragm casing 14, which is secured to the upper end of bushing 13 by set screws 21. Part 20 of the valve stem carries at its upper end a diaphragm plate 22 which may be integral therewith. The diaphragm plate resides within the chamber 23 and contacts the underside of diaphragm 24 which divides chamber 23 into 2 parts. The lower part of the chamber is in communication with the atmosphere through ports 14a and the upper part of the chamber has a connection 14b which receives a line 25. Line 25 communicates with a source of actuating fluid under pressure for energizing the motor of the valve.

It is believed that the operation of the motor-valve is apparent from its foregoing description. The diaphragm 24 is subjected to the pressure differential thereacross and urges the valve stem, made up of parts 17 and 20, downwardly to seat valve member 19 against seat ring 16. With the valve member 19 seated the pressure to be controlled is exerted against the valve member on an area equal to the area of the seat. The force of the pressure against this area urges the valve stem upwardly against the diaphragm, but due to the substantially greater area of the diaphragm as compared with the area of the seat, the pressure within the upper part of chamber 23 may be relatively small as compared with the pressure controlled. With valve member 19 lifted from its seat, which may be accomplished in a manner hereinafter explained, the area exposed to pressure within the valve body is equal to the area of the lower end of the enlarged portion of part 17 of the valve stem. Thus, it will be seen that at all times the valve stem has a part exposed to the pressure to be controlled and that the area of this part is greater with the valve member removed from its seat than with the valve member closed. Thus, when the pressure conditions within the valve body and the upper part of chamber 23 are such that the valve member is cracked from its seat force tending to unseat the valve member is increased somewhat and results in a snap action of the valve where the pressure downstream from seat 16 is less than that upstream of the seat with the valve member 19 seated which is normally the case when the valve is to be opened.

The time controller and its connection with the motor valve provides a means for relieving the pressure within the upper part of chamber 23 in order that the valve member 19 may be shifted to open position.

The time controller 10 may be any suitable conventional time controlled unit and the one illustrated schematically is the type driven by fluid under pressure but it is contemplated that the unit may be driven electrically or otherwise. The unit may be mounted upon the conduit 8 by means of a support bracket 27.

The time controller has a disc 28 which is rotatably mounted and has a plurality of pins 29 extending laterally thereof. The pins 29 are arranged circumferentially about the axis of rotation of disc 28. The disc 28 is rotated by suit-

able mechanism which, in this instance is a fluid driven motor. The fluid line 26 leads to a suitable source of drive fluid which may be the regulator 36.

5 A control lever 30 is pivoted at one end at 31 and the vent part 32 is arranged to engage the free end of lever 30 and serves as a stop to prevent rotation of the lever in one direction. A member 33 with a tapered or conical end extends 10 from lever 30 and the tapered end is adapted to engage the outer peripheries of pins 29 as the pins are passed beneath the member 33. Engagement of a pin 29 with the tapered end of member 33 and continued rotation of the disc 28 results in a raising of the free end of lever 30 from the vent part 32. On continued rotation of the disc the free end of lever 30 is again lowered into contact with the vent part 32. By adjusting the position of member 33 axially relative to lever 20 30 the length of time that the free end of lever 30 will be raised from vent part 32 upon engagement of the member 33 with each of pins 29 may be varied from a time interval of maximum length to one of very short duration.

25 Member 33 in this embodiment is shown as a screw which facilitates its axial adjustment to vary the position of its tapered end relative to lever 30. Simple rotation of the screw obviously will provide this adjustment.

30 The time control operation of lever 30 is utilized to provide for venting of actuating pressure fluid from the upper part of chamber 23. However, as a preface to the explanation of this operation, the connection of line 25 with a source of actuating fluid will be first explained. The connection 25 communicates through choke 34 with a connection 35 on regulator 36. The regulator has a connection with conduit 8 through line 37. Thus the upper portion of chamber 23 35 is charged with a constant or pilot pressure from regulator 35. However, this pressure is relieved when the lever 30 is raised from the vent part 32. The vent part contacts a resilient insert in the underside of lever 30 which closes the part. With the lever 30 raised the vent part communicates between the atmosphere and the upper portion of chamber 23 through conduit 38, valve 39, conduit 40 and connection 25. Due to the choke or restrictor 34, fluid under pressure is bled through the vent connection more rapidly than the pressure fluid is charged to the valve motor when the lever is raised from the vent part 32.

35 The valve 39 is interposed in the connection between vent part 32 and connection 25 to provide a means for preventing the relief of the pressure from the upper portion of chamber 23, on raising of lever 30, in the event the pressure within conduit 8 downstream from valve 19 exceeds a predetermined maximum. Thus, the downstream pressure in conduit 8 serves as a control pressure. The valve includes a casing made up of a cylindrical portion 41 and a port portion 42. The latter portion has an endwise passage 42a communicating with conduit 38 and a laterally extending passage 42b communicating with conduit 40. Part 42 has a central bore of enlarged diameter which communicates with the inner ends of each of the passages 42a and 42b. 40 Part 41 of the housing has a central cylindrical bore 41a in its lower end which communicates through fitting 43 and conduit 37 with the control pressure of conduit 8. Within the cylindrical bore 41a resides a piston element 44 which 45 has a seal such as an O-ring 45 in a peripheral

groove forming a seal between the pistons and the wall of the bore. A piston rod 46 extends from the piston into the central bore of part 42 of the housing and has a seal such as an O-ring in a peripheral groove forming a seal between rod 46 and the bore of parts 42. The upper end of rod 46 carries an insert of resilient material which may be rubber, synthetic rubber or the like, which is in axial alignment with the inner end of passage 42a and is adapted to seat against the end of the passage to close it when the rod 46 is shifted to an upper position. The rod will be shifted to an upper position when the pressure against the pressure face of piston 44 is great enough to collapse a resilient member 47 illustrated as a coil spring, which is lodged between lock nut 48 and the lower end of part 42 of the valve housing. Obviously when the control pressure within conduit 8 exceeds a predetermined value piston 44 will be moved upwardly causing rod 46 to close the passage 42a. Thus, the vent will remain closed and prevent escape of actuating fluid from the motor of the valve even during the intervals at which lever 30 is raised from the vent part 32. Upon subsidence of the pressure within conduit 8 the spring 47 will return the piston 44 and rod 46 to their lower position, thus opening the passage 42a whereby continued rotation of disc 28 will again effect a venting of actuating pressure from the upper portion of chamber 23.

It is contemplated that the unit, without the time controller 10, may be installed to control flow through a conduit in which case the vent for the motor of the valve will remain open at all times, so that the valve will remain open except during those times when the control pressure within conduit 8, exceeds a predetermined value which is dependent upon the strength of spring 47. This latter type installation may be used for instance in a producing well which flows naturally and wherein the string of flow tubing is equipped with at least two flow connections. In such a well installation, production normally takes place through one flow connection through a small choke and oftentimes a head of salt water, oil or the like builds up, due to the low velocity of flow through the choke containing connection. It is desirable when this occurs to increase the velocity of flow in order that the liquid head may be drawn off to again build up the pressure within the flow lines. In this type installation the controller unit of this invention, without the time controller, is installed upon the auxiliary flow pipe with valve 39 connected upstream from the valve member 19 and whenever the pressure within the flow pipe upstream of the valve falls below a predetermined amount the spring 47 forces the rod 46 downwardly to effect venting of the actuating fluid from the upper portion of chamber 23. This results in an opening of the motor valve to permit flow through the auxiliary line increasing the velocity of flow from the well tubing. However, as flow continues the liquid head, built up within the well bore, is dissipated and the control pressure within conduit 8 increases. When the pressure exceeds a predetermined amount the action of the pressure against piston 44 collapses spring 47 and closes the vent. This effects energization of the upper portion of chamber 23 and closes the motor-valve shutting off flow through the auxiliary line.

From the foregoing it will be seen that this invention is one well adapted to attain all of

the ends and objects hereinabove set forth together with other advantages which are obvious and which are inherent to the structure.

It will be understood that certain features and sub-combinations are of utility and may be employed without reference to other features and subcombination. This is contemplated by and is within the scope of the claims.

As many possible embodiments may be made of the invention without departing from the scope thereof it is to be understood that all matter herein set forth or shown in the accompanying drawings is to be interpreted as illustrative and not in a limiting sense.

Having described our invention, we claim:

1. A flow controller useable for controlling flow of fluid through a conduit comprising a pressure actuated motor-valve connectable in a conduit, the motor-valve including a part exposed to the pressure of the fluid within the valve and urged thereby in a direction to open the valve, a line connected to the motor of the valve for supplying actuating pressure thereto to hold the motor-valve closed, a vent operably connected to relieve the actuating pressure within the motor of the valve when the vent is opened, a pressure responsive element mounted to control flow through the vent, fittings to supply a control pressure to one face of the pressure responsive element to actuate it when the control pressure exceeds a predetermined value to close the vent, resilient means urging the pressure responsive element toward open position, a time controller mechanism having a part normally closing the vent and adapted to be moved periodically at predetermined time intervals by said mechanism to open position, whereby the motor-valve is normally closed by the actuating pressure when the vent is closed but is opened by the pressure of the fluid within the valve when the vent is open, and the pressure responsive element when actuated to close the vent prevents opening of the valve in response to the time controller mechanism.
2. A flow controller useable for controlling flow of fluid through a conduit comprising a pressure actuated motor-valve connectable in a conduit, the motor-valve including a part exposed to the pressure of fluid within the valve and urged thereby in a direction to open the valve, a line connected to the motor of the valve for supplying actuating pressure thereto to hold the motor-valve closed, vent means, connected with the motor of the valve, operable to relieve the actuating pressure within the motor of the valve whereby the motor-valve will be opened by the pressure of the fluid within the valve, means normally closing the vent means and adapted to move to position at desired times, and normally open valve means responsive to pressure downstream from the motor-valve for closing and maintaining closed said vent means when said downstream pressure exceeds a predetermined minimum.
3. A flow controller useable for controlling flow of fluid through a conduit comprising a pressure actuated motor-valve connectable in a conduit, the motor-valve including a part exposed to the pressure of fluid within the valve and urged thereby in a direction to open the valve, a line connected to and adapted to supply actuating pressure to the motor of the motor-valve, vent means, connected with the motor of the motor-valve, operable to relieve the actuating

pressure within the motor whereby the motor-valve will be opened by the pressure of the fluid within the valve, a valve means interposed in the vent means connection including a pressure responsive element mounted to control flow through the vent, fittings to supply a control pressure to one face of the pressure responsive element to move it into position to close the vent means, a resilient element urging the pressure responsive element against said pressure, additional serially arranged means normally closing the vent means but adapted to open the vent means at predetermined time intervals, whereby the motor-valve is normally held closed by the actuating pressure when the vent is closed but is opened by the pressure of the fluid within the valve when the vent is open, and the pressure responsive element when actuated to close the vent prevents opening of the valve in response to the time controller mechanism.

4. A flow controller useable for controlling flow of fluid through a conduit comprising a pressure operated motor-valve adapted to be interposed in a conduit, said motor-valve including a motor unit made up of a chamber with a diaphragm dividing the chamber into two parts, a valve stem with a part having a power transmitting connection with one side of the diaphragm, a valve member carried by the stem adapted to control the flow of fluid through a conduit in such manner that the force due to the pressure differential thereacross when closed is transmitted through the stem at least in part to the diaphragm in a direction to unseat the valve member, a line connected to the chamber for supplying actuating fluid on the side of the diaphragm to move it in a direction to close the valve, a vent operably connected to relieve the pressure within the said pressurized part of the chamber when the vent is open, a piston element mounted to control flow through the vent and having one face exposed to a control pressure and adapted to be actuated thereby when the pressure exceeds a predetermined value to close the vent, resilient means urging the piston toward open position, and a time controller mechanism having a part adapted to normally close the vent downstream from the piston and to be moved periodically at predetermined time intervals by said mechanism to open position, whereby the motor-valve member is normally held closed by the actuating pressure acting on the diaphragm when the vent is closed but is opened by said pressure differential when the vent is open, and the piston element when in vent closing position prevents opening of the valve in response to the time controller mechanism.

5. An apparatus for controlling flow of fluid through a conduit comprising a pressure operated motor-valve adapted to be interposed in a conduit and a time controller mechanism, the motor-valve including: a valve body with a valve member therein operable to control flow of fluid through the body, a part associated with the valve member and exposed to the pressure of the fluid within the valve and adapted to be moved thereby in a direction to unseat the valve member, a pressure responsive member operably connected to the valve member in the motor-valve, means to energize the pressure responsive member to urge the valve member toward seated position; a vent for de-energizing the pressure re-

sponsive member, the time controller mechanism having a part adapted to normally close the vent and to be moved periodically at predetermined time intervals by said mechanism to open position, a pressure responsive element mounted to control flow through the vent upstream of the time controlled part, said pressure responsive element having one face exposed to a control pressure and urged thereby in vent closing direction, resilient means urging the pressure responsive element toward open position, whereby the motor-valve is normally held closed by the actuating pressure when the vent is closed but is opened by the pressure of the fluid in the valve when the vent is open, and the pressure responsive element when actuated to close the vent prevents opening of the valve in response to the time controller mechanism.

6. A flow controller useable for controlling flow of fluid through a conduit comprising a motor-valve connectable in a conduit, the motor of said motor-valve having means for urging the valve member of the motor-valve toward open position, a line connected to the motor of the motor-valve for supplying actuating pressure thereto to actuate a pressure responsive means for closing the motor-valve, vent means, connected with the motor of the valve, operable to relieve the actuating pressure within the motor of the motor-valve whereby the motor-valve will be opened by the first mentioned means, means including a normally open pressure responsive valve responsive to the pressure downstream from the motor-valve and a time controlled valve normally closing the vent means, adapted to open the vent means at predetermined time intervals when the pressure downstream of the motor valve is less than a predetermined maximum.

7. A flow controller useable for controlling flow of fluid through a conduit comprising a pressure actuated motor-valve connectable in a conduit, the motor-valve including a part exposed to the pressure of fluid within the valve and urged thereby in a direction to open the valve, a line connected to the motor of the valve for supplying actuating pressure thereto to hold the motor-valve closed, vent means, connected with the motor of the valve, operable to relieve the actuating pressure within the motor of the motor-valve whereby the motor-valve will be opened by the pressure of the fluid within the valve, means including normally inoperative vent closing means responsive to downstream pressure to close the vent means when the downstream pressure is less than a predetermined maximum, and time controlled means normally closing the vent means, adapted to move to open position at predetermined time intervals.
